SPOOL SUPPORT AND LIFTER

Irving E. Rowe, Stonington, Conn., assignor to
The Atwood Machine Company, Stonington,
Conn., a corporation of New Jersey

Application April 21, 1934, Serial No. 721,650

6 Claims. (Cl. 242—37)

This invention relates to winding machines and particularly to a spool or bobbin supporting and rotating mechanism adapted to automatically disengage the spool or bobbin from its driving wheel when the yarn being wound on the spool breaks and also when the spool is filled to a predetermined diameter or whenever desired to have the winding stopped by the operator for any reason.

10 An object of the present invention is to improve a device for rotatably supporting a spool or bobbin being wound with yarn so that its rotation may readily be stopped when filled with yarn or when the yarn being wound breaks or runs out or manually whenever the operator desires to stop the rotation of the spool.

15 A feature of importance whereby the above named objects are obtained is that a spring actuated member, normally retained during 20 operation in a retracted position, when released by breakage of the yarn or filling of the spool with yarn to a predetermined diameter will engage and elevate a cradle in which the spool is supported.

25 And finally it is an object of the invention to provide a member hinged to the spring actuated member and normally engaging a catch on an extended lever so that when this hinged member is swung laterally or when the lever is moved about its pivot the hinged member will disengage the spring actuated member from its latch and permit this latter member to swing upward about a horizontal axis and raise the spool supporting cradle or yoke so that the spool will be 30 disengaged from the rotating wheel.

35 With the above and other objects in view, my invention includes the feature of construction and operation set forth in the following specification and illustrated in the accompanying drawing.

40 In the accompanying drawing annexed here-to and forming a part of this specification, I have shown my invention embodied in a textile winding machine for spools or bobbins having a single end wound thereon, but it will be understood that the invention can be otherwise embodied and that the drawing is not to be 45 construed as defining or limiting the scope of the invention, the claims appended to this specification being relied upon for that purpose.

45 In the drawing:

50 Fig. 1 is a complete plan view of the spool supporting and lifting device.

Fig. 2 is a side view of the device taken from the right hand side of Fig. 1.

Fig. 3 is a similar side view taken from the left hand side of Fig. 1.

Fig. 4 is a transverse sectional view taken 5 upon the plane of line 4—4 of Fig. 1, showing a spool mounted in the support and in contact with its driving roll or wheel.

Fig. 5 is a perspective view of one of the members of the supporting means looking forward from its axis of oscillation and Fig. 6 is a fragmentary horizontal sectional view.

In the above mentioned drawing, I have shown but one embodiment of the invention which is now deemed preferable, but it is to be understood that changes and modifications may be made within the scope of the appended claims without departing from the spirit of the invention.

Briefly, and in its preferred aspect, my invention may include the following principal parts; first a supporting bracket adapted to be clamped or otherwise secured to longitudinally extending members of a textile machine; second a spool supporting frame or cradle pivoted 20 to the support for free swinging movement about a horizontal axis parallel to the length of the machine; third a spring actuated member connected to the spool cradle, fourth a hinged portion of the last mentioned member movable 25 about an axis normal to the axis about which the cradle and spring actuated member oscillate, this hinged portion having a projection extending below the cradle; fifth a forwardly extended lever normally engaging the hinged portion of the spring actuated member during the winding operation and adapted when moved laterally to release the spring actuated member for swinging movement upward, which movement also raises the spool supporting cradle; 30 sixth an abutment on the cradle adapted when the spool is filled to engage and move the hinged portion to disengage the spring actuated member and permit swinging movement thereof and of the cradle; and seventh means on said hinged portion to reset the spring actuated member, the hinged portion having an extension also to prevent swinging movement of the forwardly extending lever when the cradle is raised to its upper and inoperative position. 35

40 Referring more in a particular to the figures of the drawing, I provide a supporting bracket 10 for a spool cradle or support 11 pivoted thereto for movement about a horizontal axis extending longitudinally of the machine. Preferably 45

and as shown in the drawing, the bracket 10 may be secured directly to horizontally extending supports 12 on the machine of usual or standard construction. In order to pivotally connect the bracket 10 and cradle 11 there is provided a shaft 13 extending through suitable aligned holes provided in these members. The cradle or supporting yoke 11 for the spool 14 may therefore swing upward or downward relative to the supporting bracket 10, the spool 14 being guided therein while resting upon and being rotated by a driving or friction wheel 15 directly below the spool. Slots 16 within the extended portion on opposite sides of the cradle 11 engage studs extending from opposite ends of the spool. With the cradle 11 in its lower position the spool 14 may rest with the yarn being wound directly upon the driving wheel 15. When the cradle 11 is raised by means presently to be described the spool 14 will be elevated out of contact with its driving wheel 15 and therefore the rotation of the spool will stop.

On one end of the shaft 13 pivotally connecting the cradle 11 and supporting bracket 10 is rigidly secured a member 17 to which is hinged a member 18 having a laterally extending portion 19 engaging under an extended part of the cradle 11. The hinged member 18 swings about a vertical axis normal to and intersecting the axis about which the cradle 11 moves. Normally the member 17 keyed or secured to the shaft 13 is spring pressed in a direction to force the hinged portion or member 18 and its extension 19 engaging below the cradle 11 so that when the spring is released, the parts will be moved upward. This in turn forces the cradle 11 upward when the hinged member 18 is released. To effect this spring action a helical spring 20 may be wrapped around the shaft 13, one end of which is suitably attached to the supporting bracket 10 and the opposite end of which is attached to the shaft 13. The torsion of the spring 20 is in a direction to move the hinged member 18, the member 17 and the cradle 11 upward.

On the hinged member 18 is a lateral extension or offset 21 adapted in one position of the hinged member 18 to engage under a horizontally and forwardly extending lever 22. The lever 22 is shown in full lines in Fig. 1 in its extreme right hand position. Spring 32 between lever 22 and the supporting bracket 10 normally holds lever 22 in this limited position, there being an abutment 39 on lever 22 engaging against the front of member 10 preventing further movement of lever 22 by spring 32 beyond the limit position shown in Fig. 1. When in latched position with the lever 22 the hinged member 18 is in its lower position holding the spring pressed member 17 down and permitting the cradle 11 to drop to its lowest position. To unlatch the hinged member 18 and permit this member to swing upward and raise the spool cradle 11, it is only necessary to move the hinged member 18 about its vertical axis toward the right or to move the lever 22 to the left about its axis which is also vertical. Preferably and as shown in the drawing the lever 22 is attached rigidly at the lower end of a short shaft 23 extending vertically and supported within suitably spaced holes in the supporting bracket 10. A spring 24 extending between the hinged member 18 and the supporting bracket 10 normally forces the member 18 toward its position to

engage the abutment 21 and hold the member 18 in latched position with the lever 22.

Below the abutment 21, the member 18 is continued downward as indicated at 25 in Figs. 2, 3 and 4, this surface serving to bear against the lever 22 when member 18 has been released and has swung upward. With the lever 22 in contact with this surface 25 the lever is held in its extreme left-hand position and is not therefore oscillated back and forth as the lever 22 is engaged by the traverse rod 35 with which the machine is provided. The upper end of the hinged member 18 is provided with a finger pressing portion 26 at an oblique angle adapted to facilitate depressing and laterally swinging the member 18 by the operator. By pressing upon the portion 26 the inclination of the end portion 26 is such that the hinged member naturally swings laterally as it is forced downward to again engage the hinged member 18 with the lever 22 and retain them in interlocked position. With these parts again latched winding continues.

In order to stop rotation of the spool or bobbin when filled with yarn or thread means are provided for swinging the hinged member 18 in a direction to unlatch the spring pressed member 17 and lift the supporting cradle 11 and thus raise the spool from its driving wheel 15. For this purpose a short upwardly extending projection 28 on the cradle 11 is provided with a screw 29 threaded therein to any adjusted position. The screw 29 may be locked in its adjusted position by means of a nut on the screw and bearing against the projection 28. The rearward end of the screw 29 is adjacent a lateral projection 31 of the hinged member 18. As the diameter of the wound yarn on the spool 14 increases and the cradle 11 rises the screw 29 contacts with the projecting 31 and moves the member 18 to unlatch the projection 21 on the hinged member 18 from the lever or arm 22. The supporting cradle 11 then is moved upward by spring 20 to disengage the spool from its driving wheel 15. By adjusting the position of the screw 29 the amount of yarn or thread wound upon the spool 14 before being disengaged from its driving means 15 may be widely varied.

In operation the supporting cradle 11 is permitted to swing freely so that the spool 14 may rest by gravity upon its driving wheel 15. During the winding operation the material being wound is guided by the usual grooved porcelain roll 36 mounted on the traverse bar 35 reciprocated back and forth to wind the yarn evenly the entire length of the spool. Should the thread being wound break or run out the arm 37 on which the guide roll is carried would move to a position intercepting the lever or arm 22 and thus swing this member from the position shown in full lines to the position shown in dot and dash lines. (See Fig. 1.) This movement of the lever 22 would disengage the hinged member 18 by the arm 22 riding off the abutment 21. The member 18 and the member 17 would therefore be released and would be moved upwardly by the spring 32. This movement due to the lateral projection 19 on the member 18 will cause the support 11 to be raised and thus stop further rotation of the spool. Preferably and as shown in Figs. 2, 3 and 4, a light spring 32 normally holds the lever 22 toward its latching position with member 18.

Any form of guide for the yarn being wound

may be provided, the one shown being of standard or usual form. Preferably and as indicated in the drawing, the traverse bar 35 is supported for longitudinal reciprocation upon suitable mounted rollers 38. These supporting rollers are mounted at the forward ends of brackets 39 which in turn are secured to the longitudinal members 12 on which the supporting members 10 for the cradles 11 are fixed. As rollers 38 are provided both above and below the bar 35 the bar is retained in proper position but is free to move axially. In operation of the winding machine the bar 35 is slowly reciprocated a proper distance back and forth for the width of spools being wound. Means for this purpose are not shown as they form no part of the present invention. To mount the arms 37 carrying the yarn guiding members 36 holders 41 may be suitably clamped to the rod 35. The arms 37 have a depending extension of sufficient weight to hold the arms 37, when no yarn is passing over the guides 36, in position to strike against and oscillate the arm or lever 22 to release member 18 and raise cradle 11. With yarn being wound, however, the tension is sufficient to retain the arms 37 in a position avoiding contact with the lever 22 and preventing release and upward movement of member 18 and cradle 11.

I claim as my invention:—

30 1. A spool supporting frame for textile winding machines comprising in combination, a support, a swinging frame thereon, means to support a spool in said frame, a spring pressed member normally retracted in a position to permit engagement of said spool with its driving means, a hinged portion on said spring pressed member, movable at right angles to the movement of said spring pressed member, means to latch said hinged portion to hold said spring pressed member in retracted position, and means to release said hinged member.

45 2. A spool supporting frame for textile winding machines comprising in combination, a support, a swinging frame thereon, means to support a spool in said frame, a spring pressed member normally retracted in a position to permit engagement of said spool with its driving means, an arm outstanding from said support, a hinged portion on said spring pressed member, means to latch said hinged portion with said arm to hold said spring pressed member in retracted position, and means to release said spring pressed member.

50 3. A spool supporting frame for textile wind-

ing machines comprising in combination, a support, a swinging frame thereon, means to support a spool in said frame, a spring pressed member normally retracted in a position to permit engagement of said spool with its driving means, 5 an arm outstanding from said support, a hinged portion on said spring pressed member, means to latch said hinged portion with said arm to hold said spring pressed member in retracted position, and means to move said hinged portion when said spool is filled to release said spring pressed member and raise said spool from its driving means.

4. A spool supporting frame for textile winding machines comprising in combination, a support, a swinging frame thereon, means to support a spool in said frame, a spring pressed member normally retracted in a position to permit engagement of said spool with its driving means, an arm outstanding from said support, a hinged portion on said spring pressed member, means to latch said hinged portion with said arm to hold said spring pressed member in retracted position, means to move said arm to release said hinged portion and spring pressed member and raise 25 said spool from its driving means.

5. A spool supporting frame for textile winding machines comprising in combination, a support, a swinging frame thereon, means to support a spool in said frame, a spring pressed member 30 normally retracted in a position to permit engagement of said spool with its driving means, an arm outstanding from said support, a hinged portion on said spring pressed member, means to latch said hinged portion with said arm to 35 hold said spring pressed member in retracted position, means to pivotally move said arm, independent means to pivotally move said hinged member, whereby when one of said last-named members is moved said frame is released and 40 the spool is raised from its driving means.

6. A spool supporting frame for textile winding machines comprising in combination, a support, a swinging frame thereon, means to support a spool in said frame, a spring pressed member 45 normally retracted in a position to permit engagement of said spool with its driving means, a hinged portion on said spring pressed member, means to latch said hinged portion to hold said spring pressed member in retracted position, and 50 a spring forcing said hinged portion to its latched position.

IRVING R. ROWE.
